Alfred R. Russell, St. Clair Shores, Mich.

Application November 18, 1950, Serial No. 13,039

Term of patent 7 years

(Cl. D14—18)

To all whom it may concern:

Be it known that I, Alfred R. Russell, a citizen of the United States, residing at St. Clair Shores, in the county of Macomb and State of Michigan, have invented a new, original, and ornamental Design for an Automobile Hood Ornament, of which the following is a specification, reference being had to the accompanying drawing, forming a part thereof, in which:

Fig. 1 is a front elevational view of an automobile hood ornament, showing the invention;

Fig. 2 is a side elevational view thereof;

Fig. 3 is a plan view taken on the line 3—3 of Fig. 1;

Fig. 4 is a view in perspective of the ornament shown in Fig. 1; and

Fig. 5 is a vertical sectional view taken on the line 5—5 of Fig. 1.

I claim:

The ornamental design for an automobile hood ornament, substantially as shown.

ALFRED R. RUSSELL.
